ASSEMBLING TOOL

Philip E. Hogin, Newark, N. J., assignor to
 Western Electric Company, Incorporated, New
 York, N. Y., a corporation of New York

Application January 8, 1944, Serial No. 517,571

5 Claims. (Cl. 29—235)

1

This invention relates to assembling tools, and more particularly for tools for assembling washers on articles.

In the manufacture of certain communications equipment, electrical units or articles are in some instances inserted in apertures of panels or mounting plates and are to be held in place by resilient locking rings. Also, in certain instances, the articles or units are formed partially of molded plastics, and it is important to mount them without causing damage thereto.

An object of the invention is to provide an assembling tool which is simple in structure, easily operable, and highly efficient in assembling retaining members on articles.

With this and other objects in view, the invention comprises an assembling tool including a mandrel adapted for interengagement with an article, an element adapted for movement of a retaining element longitudinally of the mandrel into registration with a groove in the article, and resilient means to force the retaining element into the groove of the article.

Other objects and advantages will be apparent from the following detailed description when considered in conjunction with the accompanying drawing, wherein

Fig. 1 is an elevational view of the assembling tool associated with an article to be secured in a mounting panel, portions of the tool being broken away;

Fig. 2 is an enlarged fragmentary sectional view of the assembling tool and article illustrating the relative positions of the parts as the retaining element nears the assembling position;

Fig. 3 is an enlarged fragmentary sectional view of the structure shown in Fig. 2, illustrating the completion of the assembling operation;

Fig. 4 is a fragmentary sectional view taken along the line 4—4 of Fig. 1;

Fig. 5 is a top plan view of the retaining element, and

Fig. 6 is an enlarged side elevational view of the retaining element, this view being taken substantially along the line 6—6 of Fig. 5.

Referring now to the drawing, attention is first directed to the unit or article to be mounted or assembled in a mounting panel 10. An aperture 11 is provided in the mounting panel 10 to receive the article or unit 12. In the present illustration the unit 12 is a socket for receiving a vacuum tube, the socket having a plurality of terminals 14 disposed one upon each side of the panel, the apertures for receiving the mounting pins of the vacuum tube not being shown, these

2

being present in the opposite side of the unit. The unit includes a central aperture 15 and a plurality of radial projections 16 providing intermediate recesses 17. The projections 16 are grooved, as at 18, short of a head portion 19. The head portion will rest upon the forward face of the panel, while grooves 18 will be partially disposed in the aperture 11 and extend therebeyond as illustrated in Figs. 1, 2 and 3.

10 A retaining element 20 is corrugated, that is, it is provided with a wavy contour as illustrated in Figs. 1, 5 and 6, the ends thereof overlapping as at 21 so as to allow for expansion of the element from its normal size shown in Fig. 5 to that 15 made necessary to pass the element over the projections 16 and into the grooves 18 adjacent the mounting panel 10.

The assembling tool includes a mandrel 24 which is tapered so that the element 20 may be 20 freely dropped over an end 25 thereof, the opposite end 26, however, being equal in diameter to the diameter of the unit or article 12 at the periphery of the projections 16. The mandrel 24 has a longitudinal aperture 27 therein enlarged 25 at its lower end 28 to receive a locating member 29, the latter having a reduced portion 30 receivable in the aperture 15 of the article 12 and providing a shoulder 31 to rest upon the adjacent surface of the article. Through this means 30 the mandrel 24 is centrally located upon the article and interlocked therewith.

During the assembling operation the article rests upon a suitable support 32, which in turn may support a multiplicity of articles 12 in an 35 equal number of apertures 11 in the mounting panel 10. The lower end 26 of the mandrel 24 is hollow, as at 33, and is provided with a plurality of projections 34 with intermediate notches or recesses 35 to form an interfitting connection between the mandrel and the article. The projections 34, as illustrated in Fig. 4, fill the outer portions of the recesses 17 of the article, their outer surfaces forming continuations of the circumferences or arcuate outer surfaces of the projections 40 45 16. Furthermore, the lower edges 37 of the projections lie in a plane common with the upper edges of the grooves 18 to guide the retaining element 20 to the grooves.

Means is provided for moving the retaining 50 element downwardly over the mandrel 24, for compressing the element until it is receivable in the grooves 18 of the article, and to force the expanded element into a contracted position in the grooves of the article. The means for accomplishing the first two functions is a tubular

member 40 whose inner diameter is substantially equal to but slightly larger than the outer diameter of the end 26 of the mandrel 24. The tubular member 40 is fixed, as at 41, to a handle 42, through the aid of an annular flange 43 integral with the tubular member. A sleeve 45 is disposed concentric with the tubular member 40 and is movable thereon a distance limited by a screw 46 carried thereby and positioned to have its inner end ride in an elongate aperture 47. The sleeve 45 has a plurality of longitudinal slots 48 therein forming resilient fingers 49 which extend beneath a lower end 50 of the tubular member 40. A compression spring 51, disposed concentric with the member 40 and in the handle 42, normally urges the sleeve 45 downwardly limited by the screw 46.

Considering now the function of the assembling tool, let it be assumed that an article 12 has been disposed in the aperture 11 of the mounting panel 10 and rests upon the support 32, as illustrated in Fig. 1. The mandrel 24 is then disposed in interfitting engagement with the article, the portion 30 automatically centering the mandrel with the article and the shoulder 31 assuring the location of the projections 34 with respect to the grooves 18. The retaining element 20 may then be dropped over the upper end of the mandrel, after which the unit, including the tubular member 40, the sleeve 45 and the handle 42, may be disposed over the mandrel and brought to rest upon the retaining element 20. By applying suitable force to the handle 42, the retaining element 20, through the downward movement of the tubular member 40, will be forced downwardly over the mandrel and caused to expand due to the tapering contour of the mandrel. Through the provision of the projections 34, a continuous circular contour is provided for the retaining element until it reaches the grooves 18. When the retaining element 20 has been moved to a position where it engages the adjacent surface of the panel 10, additional force is required to partially compress the element so that it may be moved into the grooves 18. This is brought about by continued force through the handle 42 to the member 40.

During the downward movement of the unit portion of the assembling tool over the mandrel, the resilient fingers of the sleeve near their lower ends, that is, adjacent the element 20, have been forced outwardly due to the expansion of the element, and the force created in the fingers 49 is sufficient to contract the expanded and partially flattened retaining element 20 and thus force it into the grooves 18 of the article. Through the aid of the spring 51, the resilient fingers 49 extend beneath the end 50 of the member 40 to extend around the element 20. The spring is, however, compressed when the sleeve 45 comes to rest upon the panel 10 and during compression of the element.

By the provision of the assembling tool, the counteracting force built up in the retaining element during the steps necessary to expand it and to partially flatten it and direct it into the grooves 18, is kept from the article 12, eliminating possible damage to the article and assuring the positive interfitting connection of the retaining element, the article and the mounting panel. Furthermore, the mandrel assures positive and uniform expansion of the retaining element, during which time uniform forces are created in the contracting fingers 49, which forces may be applied equally to the retaining element

once it is compressed sufficiently to be received in the grooves to cause uniform contraction of the element and positive locking of the article thereby to the panel.

Although specific improvements of the invention have been shown and described, it will be understood that they are but illustrative and that various modifications may be made therein without departing from the scope and spirit of this invention as defined by the appended claims.

What is claimed is:

1. A tool for assembling a split resilient cylindrical corrugated retaining ring, with flutes whose rise and fall are parallel with the axis of the ring, in a groove of an article comprising a mandrel adapted to receive the retaining ring on one end thereof and direct it to the said groove, means movable relative to the mandrel for moving the retaining ring longitudinally of the mandrel to a position adjacent the said groove and compress the retaining ring to partially flatten the flutes thereof, whereby the ring may be subsequently disposed in the groove, and means to apply pressure laterally to the compressed retaining ring to force it into the said groove.

2. A tool for assembling an expansible and contractible retaining ring in a groove of an article disposed short of an end thereof having recesses in the periphery thereof, the tool comprising a mandrel tapered from one end adapted to receive the retaining ring to the other end which is equal to or larger than the periphery of the article and which has projections for interengagement with the said end of the article in the recesses thereof, whereby the retaining ring may be expanded for movement over the end of the article and into the groove thereof, a member movable longitudinally of the mandrel to move the retaining ring therewith on the mandrel to the groove, and a flexible element in contact with the outer periphery of the ring flexed by the expansion of the retaining ring to contract the ring and force it into the groove when said groove is reached by the ring.

3. A tool for assembling an expansible and contractible retaining ring in a groove of an article disposed short of an end thereof having recesses in the periphery thereof, the tool comprising a mandrel tapered from one end adapted to receive the retaining ring to the other end which is equal to or larger than the periphery of the article and which has projections for interengagement with the said end of the article in the recesses thereof, whereby the retaining ring may be expanded for movement over the end of the article and into the groove thereof, a member movable longitudinally of the mandrel to move the retaining ring therewith on the mandrel to the groove, and a flexible element having a plurality of fingers in contact with the periphery of the ring to be flexed by the expansion of the retaining ring to contract the ring and force it into the groove when said groove is reached by the ring.

4. A tool for assembling an expansible and contractible corrugated retaining ring in a groove of an article disposed short of an end thereof having recesses in the periphery thereof, the tool comprising a mandrel having one end substantially equal in cross-section to the said end of the article and tapering to the other end adapted to receive the retaining ring, projecting portions of the mandrel receivable in the recesses of the said end of the article to form interengagement.

between the mandrel and the article and to close the recesses, a member movable longitudinally of the mandrel to move the retaining ring therewith to the groove to cause expansion of the ring on the mandrel, and means to contract the compressed ring into the groove.

5. A tool for assembling an expansible and contractible corrugated retaining ring in a groove of a hollow article disposed short of an end thereof having recesses in the periphery thereof, the tool comprising a mandrel having one end substantially equal in cross-section to the said end of the article and tapering to the other end adapted to receive the retaining ring, a member movable longitudinally of the mandrel to move the retaining ring therewith to the groove to cause expansion of the ring on the mandrel, projecting portions of the mandrel receivable in the

said recesses to hold the retaining ring free of the article until the ring reaches the groove, and an element carried by the mandrel and receivable in the hollow article to center the mandrel with the article.
